CARRYING CASE FOR A MICROSCOPE

John T. Armbruster, Niagara Falls, N.Y., assignor to
American Optical Company, Southbridge, Mass., a
voluntary association of Massachusetts

Filed Nov. 27, 1963, Ser. No. 77,598

Term of patent 14 years

(Cl. D87—5)

FIG. 3

FIG. 4

FIG. 5

FIG. 6

FIG. 1 is a front perspective view of a carrying case for a microscope showing my new design, in closed condition;

FIG. 2 is a similar view but showing the same in open condition;

FIG. 3 is a front elevational view thereof;

FIG. 4 is a right-side elevational view thereof;

FIG. 5 is a top plan view thereof; and

FIG. 6 is a bottom plan view thereof.

The essential features of my design are shown in full lines in the drawings.

I claim:

The ornamental design for a carrying case for a microscope, as shown and described.
